UNITED STATES PATENT OFFICE.

WILLIAM JANICKI, OF CHICAGO, ILLINOIS.

DESIGN FOR A CHRISTENING CARD.

60,990.

Specification for Design.

Patented May 23, 1922.

Application filed March 14, 1921. Serial No. 452,330. Term of patent 3½ years.

To all whom it may concern:

Be it known, that I, WILLIAM JANICKI, a citizen of the United States, residing at Chicago, in the county of Cook and State of Illinois, have invented a new, original, and ornamental Design for Christening Cards, of which the following is a specification, reference being had to the accompanying drawings, forming part thereof.

The figure is a front elevation of the card embodying my new design.

I claim:

The ornamental design for a christening card as shown.

WILLIAM JANICKI.
